UNITED STATES PATENT OFFICE.

ELMER H. KING, OF CAPE ELIZABETH, MAINE.

CHEMICAL SUBSTANCE.

No Drawing.

Application filed February 2, 1922. Serial No. 533,671.

The present invention is directed to new compounds and methods of making the same, said compounds being of particular utility in the treatment of various human ailments.

5 Perhaps the most important use is in the treatment of those diseases of the body cells or tissues coming under the general classification of sarcomata, carcinomata, glandular hypertrophies and chronic inflammation.

10 The compounds are in a colloid-like state, and according to the present preferred method are prepared by combining alkaloids with desaccharated glucosides. The term "desaccharated glucosides" is intended to include such compounds as remain after splitting off sugar components of glucosides by any suitable process.

The use of the compounds in the treatment of the diseases mentioned above has demonstrated that the alkaloids are desirable because of their specificity and because of their heptaphoric property of binding or holding the desaccharated glucosides; and the desaccharated glucosides are employed because 25 they are capable of performing the desired action upon certain pathological cells, that is, for their toxophoric effect.

The compositions of matter of the present invention comprise two elements or radicals, 30 namely a toxophore, or toxic substance, and a heptaphore, or binding substance, the heptaphore being of such a nature that the molecules of the compositions of matter of the present invention are generally in an aggregated state, and by reason of the isocolloidal 35 property of the compositions, the aggregated particles are capable of assuming decreasing orders of magnitude with increasing dilution.

The toxophore may be desaccharated glucoside, but it may also be a substance unrelated thereto, as for example, salvarsan, or other metallo-organic compound, which may contain mercury, arsenic, silver, etc.; while the heptaphore is generally an alkaloid or 45 some compound derived therefrom. The "binding" quality of the heptaphore is apparently due to the polymerization, or the colloidal, or as it may be termed, the isocolloidal, of the composition of matter of which it is a radical; and it is a function of the alkaloid employed.

As far as known, it is new to combine alkaloids and desaccharated glucosides, in fact heptaphores and toxophores. The desaccharated glucosides act as acids and the alkaloids act as bases to form more or less

definite salts. It is also new to produce such salts in a colloid-like state.

Preferably, the alkaloids employed are quinine, quinicine and caffein, and these may be used in various forms. For example, quinine has been employed as the alkaloid itself, as the hydrochloride, and as the dihydrochloride. Processes for making the compounds of this invention from ingredients including these three forms of quinine, where-in the quinine is converted into the isomeric quinicine, are set forth hereinafter. Cinchonine, cinchonidine, and quinidine, and their hydrochloric and sulphuric acids salts may also be employed, and of these the sulphates and disulphates are preferred. Emetin, and perhaps atropin and morphine, may be used as alkaloids in the preparation of the compounds; and compounds containing a quinoline nucleus are of particular value. Quinine and quinidine, lævo-rotatory and dextro-rotatory respectively, are isomeric and are converted into quinicine by boiling in water or in an aqueous acid solution, such, for example, as acetic or hydrochloric acid. Cinchonine and cinchonidine which are isomers, are converted by similar methods into cinchonicine which is an active binding agent. Cupreine and cupreidine are likewise converted into functionally active binding substance. Other very useful substances are: Cinchonicine, hydro- (or dihydro-) quinine, hydro- (or dihydro-) quinidine, hydro- (or dihydro-) cinchonine, hydro- (or dihydro-) cinchonidine, hydro- (or dihydro-) quinicine, hydro- (or dihydro-) cinchonicine.

Among the desaccharated glucosides which have been used may be mentioned the phenolic coloring matters, and in particular those of the flavonal, anthocyan and dihydropyran groups. It may be stated that weak phenolic acids generally are of value and that very good results have been obtained from hematoxylin, brazilin, quercitin, vitexin, fisetin and the morin of fustic.

The compounds obtained from the substances mentioned above, their derivatives, substitutes or homologues, have varying degrees of efficiency for different purposes. Generally, however, it is preferred to use hematoxylin as the acid and quinicine as the base, since the compounds resulting from combining these substances as a rule have the greatest efficiency.

For the purpose of disclosing the method of preparing the compounds of the present

invention, three processes will be described, the first employing alkaloid quinine as a reagent, the second quinine hydrochloride and the third quinine dihydrochloride.

5 *First method.*

1. Add a gram-molecular weight of de-saccharated glucoside (for example, hematoxylin) to 10,000 mils boiling one-half normal hydrochloric acid, and continue the boiling.
2. To the boiling solution resulting from the above step add a gram-molecular weight of quinine, and continue boiling for about 20 minutes.
3. Cool to about 20° C. and adjust the volume to 10,000 mils.
4. The excess acid may be removed by dialysis or other suitable process, such as neutralization with a solution of sodium bicarbonate, and the desaccharated glucoside itself may be used as the indicator.
5. Filter through ordinary filter paper.
6. Sterilize, by heating to 110° C.

25 *Second method.*

1. Add a gram-molecular weight of de-saccharated glucoside (for example, hematoxylin) to 10,000 mils of boiling one-half normal hydrochloric acid.
2. Add to a gram-molecular weight of quinine hydrochloride in saturated aqueous solution, a saturated aqueous solution of sodium bicarbonate, until effervescence ceases.
3. Add boiling solution (2) to boiling solution (1), noting that solution (2) contains a precipitate which should be added along with the liquid, and boiled together for about 20 minutes.
4. Cool to about 20° C. The volume should be adjusted to 10,000 mils.
5. Remove the excess of acid, filter and sterilize as in the first example.

45 *Third method.*

1. Add a gram-molecular weight of quinine dihydrochloride to 10,000 mils of boiling water, and continue to boil for about 20 minutes.
  2. To the foregoing boiling solution add a gram-molecular weight of the desaccharated glucoside (for example, hematoxylin). Add the desaccharated glucoside bit by bit, waiting between such added portions until effervescence ceases.
  3. Remove the excess of acid, filter and sterilize as in the other examples.
- In each of the above given methods, boiling results in the production of quinicine, and if desired, quinicine may be used as a starting material in my process.
- Other methods may be used for the preparation of my material, as one example of which the following is given:
- 65 1. About thirty (30) parts of a concen-

trated solution of hydrochloric acid (having a strength of about 30% to 33%) is mixed with about ninety (90) parts of water. This is merely a very convenient method of preparing hydrochloric acid solution of the desired strength and any other method may be used. This solution of hydrochloric acid is heated to boiling.

2. Twelve (12) grams of hematoxylin are gradually added to the above mentioned boiling solution of hydrochloric acid.

3. The vessel containing the resulting mass is then maintained at a temperature of 40° C., preferably in a thermostat, whereupon, after about twenty-four (24) hours, crystals of hematoxylin hydrochloride separate out. These crystals are collected and the mother liquor may be discarded.

4. One mol of the alkaloid quinine is dissolved in carbon bisulphide or other solvent of the alkaloid which is not miscible with water. The carbon bisulphide is used merely as a special solvent and the amount thereof is more or less immaterial. By way of a specific example, however, it may be stated that a small excess of carbon bisulphide over the amount necessary to dissolve the stated quantity of alkaloid will produce good results.

5. One mol of hematoxylin hydrochloride, produced as indicated above, is dissolved in water. Here, also, the water is used merely as a solvent, and the amount thereof used is more or less immaterial, but by way of specific example it may be stated that a slight excess over the amount necessary to dissolve the given quantity of hematoxylin hydrochloride will produce good results.

6. The solution of alkaloid in carbon bisulphide and the solution of hematoxylin hydrochloride in water are brought into contact with each other, preferably with stirring. On standing, an interface will be formed between the two solutions as they are immiscible, the aqueous solution being supernatant. Crystals of quinine hematoxylin are formed at this interface and drop into the carbon bisulphide layer. These crystals may be removed as rapidly as they are formed, provision being made for the renewal of quinine in the carbon bisulphide or other solvent therefor used, and also for the renewal of hematoxylin hydrochloride in the water or other solvent therefor used.

The solutions obtained by practicing the above processes are in a colloid-like state and may be used hypodermically in the treatment of the diseases. The hematoxylinates of the members of the cinchona group and possibly other alkaloids are barely soluble in water, while such hematoxylinates are more soluble and therefore can be made available in a more concentrated colloid-like condition if there is another acidic radical attached to a basic valence of the alkaloidal radical. For

this reason I often prefer to use a hydrochloride or other salt of the alkaloid; and when ever the compound, consisting merely of the alkaloid radical and the desaccharated glucoside radical, is too insoluble, I prefer a compound having an additional acid radical attached to the alkaloid radical. A great many alkaloids have two amino groups, and as the desaccharated glucoside generally attaches itself to one of these amino groups, it is possible to increase the solubility and the concentration of the compound in a colloid-like solution by adding a hydrochloric or other acid radical to the compound, which acid radical apparently attaches itself to the other amino group. Mixtures of different solutions, containing various alkaloids and desaccharated glucosides, may be employed in accordance with the diseases to be treated.

20 Caffein or its corresponding salt may be substituted for the quinine or either of its hydrochlorides in the above processes. In accordance with the effect desired the caffein products may be used alone or admixed with the quinine (or quinicine) products in varying proportions. Preferably quinicine is employed as the alkaloid and hematoxylin as the desaccharated glucoside, although the other alkaloids and desaccharated glucosides give good results. Theobromine compounds are almost but not quite equal to the corresponding caffein compounds.

25 Slight immaterial changes can be made in a side chain of hematoxylin either by addition, subtraction or substitution without affecting its action to any great extent, and the same is more or less true of various other materials mentioned herein.

30 Quinine, or rather its derivatives, is best suited for preparing the salt to be used for the treatment of undifferentiated protoplasm and caffein is best for differentiated. Hence quinine, or its derivatives, is best for the majority of the sarcomata; while some require both quinine and caffein-hematoxylinate. Most of the cancers require admixture of both, in relative proportions approximately determinable by judgment of how much of them is made up of differentiated (epithelial) tissue, and of how much undifferentiated (fibrous) tissue. A skilled practitioner can determine within very close limits what shall be used for the majority of the sarcomata (the remaining sarcomata, fairly easily recognized, belonging, so far as treatment goes, with the carcinomata), what shall be used in cancers, what in pure glandular (epithelial) hypertrophies, and what in chronic inflammations.

35 The products are to be bottled ready for use, as they are fairly stable and have been kept in sealed glass containers for six months and found efficient.

40 It is important to note that the efficiency of the products is more or less proportional to the

45 stability of the hydrogen ions and that the problem is to hold a delicate substance in unstable equilibrium until the patient receives it.

50 Investigations indicate that the preferred preparation is a new definite chemical substance in solution, viz: quinine-hematoxylinate, or rather, quinicine-hematoxylinate. This substance is, however, so delicate that in the process of its isolation, oxidation occurs, 75 resulting in quinicine-hematinate, which is incapable of reduction.

55 By employing the various alternative substances as reagents new definite chemical compounds are obtained, all possessing to a greater or less degree the curative properties of the quinine-hematoxylinate, among which may be mentioned, it being understood that the list is incomplete:—quinine or quinicine-brazilinate, quinine or quinicine-queracetinate, 80 quinine or quinicine-vitexinate, quinine or quinicine-querectinate, quinine or quinicine-fisetinate, caffein-hematoxylinate, caffein-brazilinate, caffein-queracetinate, caffein-vitexinate, 85 caffein-querectinate, caffein-fisetinate, 90 morphin-fisetinate, morphin-hematoxylinate, atropin-morinate, atropin-hematoxylinate.

95 A probable theory of the action of the new compositions of matter is that the mechanism of destruction of abnormal cells thereby consists of two phases, one physical and the other chemical. The physical phase is due to the colloid-like nature of the compounds, and to the peculiar surface activity of the abnormal cells resulting in adsorbing or incorporating 100 colloid-like particles of the compounds which consist of a more or less large number of molecules into the cell bodies. After the adsorption or incorporation, depolymerization 105 of the colloid-like particles begins; molecules of the substance are dispersed throughout the cell by the action of free water entering the cell; and after depolymerization, that is, assumption of the molecular disperse state the chemical action begins, whereby the substance 110 exerts its destructive effect on such cells. The dispersion is comparatively slow and gradual, as is the hydrolyzation, with the result that the colloid-like material affixed to the cells has the function of a reservoir for supplying a 115 reducing agent at the cell.

120 Although several compounds have been described and several methods for producing the same, it is to be distinctly understood that the invention is not limited to the particular compounds or methods recited, but includes modifications and changes which come within the scope of the appended claims.

125 This application is a continuation in part of my application Serial No. 374,904, filed April 19, 1920.

Having thus described the invention, what is claimed as new and desired to be secured by Letters Patent is:

130 1. A medical composition of matter com-

prising the combination of a quinicine radical and a weak phenolic acid radical.

2. A medical composition of matter comprising the combination of a quinicine radical and a radical of a member of the dihydropyran group.

3. A medical colloid-like composition of matter in solution comprising the combination of a quinicine radical and a radical of a phenolic coloring matter.

4. A medical colloid-like composition of matter in solution comprising the combination of a hematoxylin radical and a quinicine radical.

15 5. A medical colloid-like composition of

matter comprising a salt, a component of which is capable of causing deterioration of certain pathological cells and another component of which is a binding agent for the deteriorating agent, said colloid-like material 20 having the capability of affixing itself to said pathologic cells and of passing into a more disperse state on dilution by solvent thereof in and at the cells, said salt when in the dispersed condition being easily hydrolyzable by 25 said solvent to make the deteriorating agent gradually available.

In testimony whereof I hereunto affix my signature.

ELMER H. KING.
